US0D1110720S

(12) **United States Design Patent** (10) **Patent No.:** **US D1,110,720 S**
(45) **Date of Patent:** **** Feb. 3, 2026**

(54) **LUGGAGE CASE**

(71) Applicant: **GUANGZHOU LUGGEX TECHNOLOGY CO. LTD.**
Guangzhou (CN)

(72) Inventor: **Kaihong Wang**, Guangzhou (CN)

(73) Assignee: **GUANGZHOU LUGGEX TECHNOLOGY CO. LTD.**
Guangzhou (CN)

(**) Term: **15 Years**

(21) Appl. No.: **29/900,337**

(22) Filed: **Aug. 20, 2023**

(51) LOC (15) Cl. **03-01**

(52) U.S. Cl.

USPC **D3/279**

Assistant Examiner — Jane Yoon

(57) **CLAIM**

The ornamental design for a luggage case as shown and described.

DESCRIPTION

FIG. 1 is a front, left and top perspective view of the luggage case showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof; and,

FIG. 8 is a rear, right and bottom perspective view thereof.

The broken lines illustrate portions of the luggage case that form no part of the claimed design.

1 Claim, 8 Drawing Sheets
